L. L. MINCER

OPHTHALMIC TEST CHART

Original Filed Aug. 16, 1921

UNITED STATES PATENT OFFICE.

LOUIS L. MINCER, OF ROCHESTER, NEW YORK.

OPHTHALMIC TEST CHART.

Application filed August 16, 1921, Serial No. 492,793. Renewed August 18, 1924.

To all whom it may concern:

Be it known that I, LOUIS L. MINCER, a citizen of the United States, and resident of Rochester, in the county of Monroe and 5 State of New York, have invented certain new and useful Improvements in Ophthalmic Test Charts; and I do declare the following to be a full, clear, and exact description of the same, taken in connection with 10 the accompanying drawings, forming a part of this specification.

My invention relates to ophthalmic test charts of the kind used in the examination of eyes for properly fitting spectacles or 15 eye glasses, and has for its principal object the construction of a chart which is simple, convenient to use, attractive in appearance, and which can be manufactured economically. A further object of my invention is to provide a chart in which a 20 test card can be readily inserted or removed therefrom. A still further object of my invention is to provide a test chart which is properly illuminated by means of electric lamps conveniently controlled by the operator. More specifically the object of my 25 invention is to provide a test chart comprising a frame having electric lamps positioned at its sides and having a handle and a switch adjacent to the handle for controlling the electric lamps. To these and other ends my invention consists in certain 30 improvements, arrangement, and combination of parts as will hereinafter more fully appear and particularly pointed out in the 35 claims at the end of this specification.

In the drawings:

Fig. 1 is a front elevation of an ophthalmic test chart constructed according to my 40 invention,

Fig. 2 is a plan view of the same, and

Fig. 3 is a section on the line 3^x—3^x of Fig. 1.

Referring particularly to the drawings, 45 my improved chart comprises a frame 1 constructed of sheet metal and turned up or rolled forwardly at its side edges to form substantially cylindrical housings 2 and 3 open at their inner sides for a purpose presently to be described. At its lower edge, it has formed integral therewith, a tubular housing 4 open at its outer ends adjacent the lower ends of the housings 2 and 3 and also having an opening

5 intermediate its ends. Thus constructed 55 the frame 1 is substantially rectangular in form and neat in appearance.

Secured to its forward face by means of rivets or other suitable securing means is a rectangular frame 6, spaced from the 60 front wall of the frame 1 and open or free from the frame 1 at its upper edge, as at 7, to provide a slot or pocket into which an ophthalmic test card may be conveniently inserted. Within the housings 2 and 3 are 65 provided electric lamp sockets for the lamps 8 and the inner walls of said housings may be highly polished or silvered in order to direct or reflect the light from the lamps 8 through the open sides of the housings 70 upon the front face of the frame 1 or the card exposed through the frame 7. The electric conductors connected with the lamps 8 are drawn through the tubular member 4 and through the opening 5 where they are 75 connected with a suitable switch 10.

The switch 10 is mounted in a tubular member 11 secured by rivets or other suitable means to the rear face of the frame 1 in position to communicate with the opening 5 in the member 4 and open at its lower end. The tubular member 11 is provided with openings in its front and rear walls through which buttons 12 and 13 for controlling the switch 10 slideably project. Connected with the outer end of the switch 85 are the conductors 14 leading to any suitable source of electric current.

For convenience in using the chart, I provide the same with a suitable handle 15, 90 said handle is tubular so that the conductors 14 may extend therethrough. At its upper end the handle 15 is slightly reduced in diameter so that it may be conveniently inserted in the outer end of the tubular 95 member 11 and secured in position by means of a screw inserted in the tapped opening 16 in the member 11 for engagement with the handle. It will be noted that by this construction the handle may be readily detached from the chart or secured thereto when it is desired to use the chart as a hand instrument. In order to improve the appearance of the chart extensions 17 and 18 extending laterally of the tubular member 11 may be provided and may be conveniently secured to the rear of the handle adjacent its upper end to be removed there-

with or, if desired, they may be permanently secured to the chart by any suitable or convenient means.

It will be noted that by the arrangement of the lamps within the tubular reflectors, direct rays of light are prevented from reaching the eyes of the patient and the light from the lamps may be uniformly distributed over the front face of the test card.

I have also provided means for supporting a close muscle chart for muscular tests, between the free edges of the reflectors 2 and 3. Said means comprises the parts 19 and 20 integral with the reflectors 2 and 3 and having card retaining extensions.

Having described my invention what I claim and desire to secure by Letters Patent is:

29 1. A test chart holder comprising a sub-

stantially rectangular frame, adapted to hold a test card, a lamp supported at each side of said frame, a switch supported on said frame intermediate said lamps, conductors connecting said switch with said lamps, a tubular handle secured to said frame adjacent said switch and conductors leading from the switch through the handle to a source of power.

2. A test chart holder comprising a substantially rectangular frame adapted to hold a test card, a lamp supported at each side of said frame, a reflector associated with each of said lamps and adapted to concentrate the light of the lamps on the test card, and means for supporting a muscle test chart between said reflectors and spaced from the test card.

LOUIS L. MINCER.
